BICYCLE SHED

Gunnar S. Jenson, 1301 N. Michigan St.,
South Bend, Ind. 46617

Filed Mar. 4, 1974, Ser. No. 448,060

Term of patent 14 years

Int. Cl. D25—03

U.S. Cl. D13—1 R

Fig. 1

Fig. 2

Fig. 3

Fig. 4

Fig. 5

Fig. 6

FIG. 1 is a perspective view of a bicycle shed embodying the present design;

FIG. 2 is a top plan view of the bicycle shed shown in FIG. 1;

FIG. 3 is a front elevational view;

FIG. 4 is an elevational view of the side opposite that shown in FIG. 1;

FIG. 5 is a rear elevational view; and

FIG. 6 is an enlarged perspective view of the bicycle shed embodying the present design with the door of the shed open, showing the internal design configuration of the shed embodying the present design, including a bar for upending a bicycle and holding it in an upended position.

I claim:

The ornamental design for a bicycle shed, substantially as shown and described.
